NEEDLE MOTION FOR AXMINSTER LOOMS

William W. Robertson, Northboro, Mass., assignor to Crompton & Knowles Loom Works, Worcester, Mass., a corporation of Massachusetts

Application December 21, 1936, Serial No. 116,967

6 Claims. (Cl. 139—123)

This invention relates to improvements in needle motions for Axminster looms and it is the general object of the invention to permit the continuous running of the heavy parts of the needle motion while at the same time permitting a dwell in the needle movement.

As heretofore constructed Axminster looms have had large intermittent gears with spaced sections of teeth to actuate a pinion connected to shafting and other heavy parts. As a result of this construction it has been necessary to stop and start a relatively large mass of moving parts for each insertion of the needle. The reason for the intermittent motion has been to permit the needle to remain at rest while the lay beats forwardly subsequent to the laying of weft. It is an important object of my present invention to permit the dwell in the needle motion and at the same time move the heavy parts of the mechanism continuously, thereby reducing the cost of operation and the likelihood of breakage and wear.

It has also been customary in Axminster looms to provide an oscillating segment with gear teeth to mesh with the pinion connected to the drum which actuates the cable or rope for the needle motion. In the past the segment has been so constructed that any motion thereof has required a corresponding turning of the pinion with consequent movements of the needle. It is a further object of my present invention to modify the segment as heretofore used by the addition of arcuate dwell areas to cooperate with a lock connected to the pinion. By this construction the pinion is given the requisite amount of angular motion, after which the lock comes into action and cooperates with the dwell on the segment to hold the pinion and therefore the needle stationary while the segment continues to move. These advantages are achieved without lengthening the guide rail.

When the needle is fully inserted into the shed the selvage shuttle passes through the loop of weft carried by the needle and this operation requires an appreciable amount of time. If desired I may also provide a dwell on the segment which operates to hold the needle stationary while fully inserted into the shed to allow more time for the selvage shuttle to loop the weft. I do not deem this an essential feature of my invention, inasmuch as the driving arm for the segment has a crank motion which gives the effect of a temporary dwell in the motion of the needle at this time. This dwell due to the crank will ordinarily

suffice, but where a longer dwell is desired the second dwell on the segment can be employed.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a front elevation of the needle motion of an Axminster loom having my invention applied thereto,

Fig. 2 is a vertical section on line 2—2 of Fig. 1,

Figs. 3, 4, 5 and 6 are diagrammatic views showing the relation of the needle moving parts in different positions of the segment, and

Fig. 7 is a plan view of the pinion, lock therefor and segment cooperating therewith, taken in the direction of arrow 7, Fig. 1.

Referring to the drawing, I have shown the needle frame 10 of an Axminster loom the weaving instrumentalities of which will ordinarily lie to the left of the structure illustrated in Fig. 1 and which have been omitted because they are well understood. Supported on the upper part of the frame 10 is a needle rail 11 to support and guide a needle carrier 12 which is reciprocated along the rail by a cable 13 to move a weft laying needle N. The lay extends around an inner sheave 14 rotating on a fixed pin 15 and a drum 16 is provided to have attached thereto one end of the cable 13. The opposite end of the cable is also secured to the drum in well-known manner and extends to the right as viewed in Fig. 1 to pass around a movable sheave 17 rotatably mounted as at 18 on a slack taking-up arm 19 pivotal about an axis 21. A weight 26 connected to the arm 19 tends to move the latter to the right as viewed in Fig. 1 for the purpose of holding cable 13 taut. The details of the structure shown at the right hand end of the rail for controlling the movable sheave 17 may be the same as that shown in my prior Patent No. 1,724,315 and of itself forms no part of my present invention.

I provide also a continuously running shaft 30 mounted in suitable bearings and having mounted thereon a relatively large beveled gear 31 which meshes with a corresponding bevel pinion 32 secured to a shaft 33. The latter also rotates in appropriate bearings and has keyed thereto a crank arm 34 which may turn in a clockwise direction as indicated by arrow a in Fig. 1. The crank arm 34 therefore rotates continuously and preferably though not necessarily with a uniform angular rate.

The matter thus far described is of known con-

5 10 15 20 25 30 35 40 45 50 55 60 65 70 75 80 85 90 95

struction, the large beveled gear 31 having teeth entirely around the periphery thereof and replacing the usual intermittent bevel gear, but being similar to the gear set forth in patent to Paine 5 1,739,171.

A segment 40 is pivoted to the needle frame as at 41 and is attached to the crank arm 34 by a connector 42, the point of attachment between the connector and the segment being adjustable 10 as designated generally at 43 in Fig. 1 to permit a moderate adjustment in the throw of the segment. A rod head 44 permits adjustment of the length of the connector 42.

The segment has a series of gear teeth 45 15 adapted for meshing with a pinion 46 keyed to a shaft 47 rotatable in bearing 48 carried by the frame 10. The drum 16 is also secured to the shaft 47 and therefore rotates with the pinion 46.

Located at the left of the gear teeth 45 and 20 mounted on and moving with the segment is a locking dwell arm 60 having an arcuate surface 61 concentric with the axis 41. This dwell as shown in Fig. 1 extends beyond and to the left of the left tooth of the section 45 and is adapted 25 for engagement with a lock 52 also having an arcuate concave surface 53 of the same radius as the surface 51. The lock 52 and pinion 46 are both fast with respect to the shaft 47 and drum 16. The dwell 60 does not extend for the whole 30 length of the segment but is comparatively short, terminating as suggested in the drawing at the left hand tooth of the segment. The locking surface 61 comes into operation when the needle is to be held temporarily at rest out of the shed while 35 the lay beats up.

As already stated I may also use a second dwell arm 50 on the right end of the segment, the second arm being similar in construction to the dwell 60 and having an arcuate surface 51 concentric 40 with axis 41 and adapted for cooperation with the lock 52.

When the needle is fully inserted into the shed the surface 53 of the lock will engage the surface 51 of dwell arm 50 as shown in Figs. 1 and 3. 45 When the crank arm 34 rises from the position of Fig. 1 the segment will move to the right and the dwell 50 will slide to the right under the lock 52. After a short travel of the crank arm the first or right hand tooth of the section 45 will engage the 50 pinion 46 and by this time the left hand end of the dwell 50 will have arrived approximately at a point on a line connecting the axes 41 and 47. Hence the lock is free to turn with the pinion when the latter is rotated by the teeth of the segment. This position is indicated diagrammatically in Fig. 4 of the drawing.

As the crank arm 34 rotates in the direction of arrow *a*, Fig. 1, the segment will continue to move to the right and the pinion 46 will be rotated the 60 desired number of times, the lock 52 turning therewith. Fig. 5 shows an intermediate position between the beginning and ending of the working stroke of the segment with the crank moving the segment with an accelerating rate of speed. Rotation of the pinion turns the drum and the latter unwinds one end of the cable 13, and winds up the other end, thereby causing sliding movement of the carriage 12 along the rail 11 to the right as viewed in Fig. 1 to withdraw the needle *N* from 65 the warp shed not shown.

When the last or left hand tooth 45 leaves or is about to leave the pinion 46 the lock 52 will assume an angular position which permits the surface 61 of dwell 60 to slide under the surface 53 70 of the lock, after which continued motion of the

crank arm 34 will move the dwell 60 under the lock without causing rotation of the pinion 46, as suggested in Fig. 6. At this time the needle is withdrawn from the shed and the lay beats up 5 the weft laid by the needle.

Continued motion of the crank arm 34 will now start a left hand motion of the segment and cause the left hand tooth thereof to engage the pinion 46 at approximately the same time that the inner or right end of dwell 60 arrives on the line joining 10 centers 41 and 47. The lock 52 therefore no longer restrains the pinion and the latter has a reverse motion to move the needle into the shed. The segment and pinion will again pass through the position suggested by Fig. 4 and as the arm 34 15 approaches alignment with the connector 42 the surface 51 will slide under surface 53 of the lock and hold the pinion 46 against rotation during the latter part of the left hand motion of the segment.

The amount of dwell on the part of the needle, which is determined by the time during which the teeth 45 move while out of mesh with the pinion 46, can be determined by changing the 20 length of connector 42.

From the foregoing it will be seen that I have provided a needle motion for Axminster looms wherein the heavy parts, such as the bevel gear 31 and parts driven thereby, are moved continuously, but the needle is given its desired dwell 30 periods while the lay is beating up weft because of cooperation of the dwells 50 and 60 with the lock 52. It will further be seen that the segment constitutes a member having working and locking strokes during the first of which the drum is 35 turned to cause motion of the needle and during the second of which the drum is locked against rotation while the segment continues to move. As previously stated the dwell 50 is not necessary but is described in order to indicate how the needle may be brought to rest an appreciable period should more time be desired for the selvage shuttle motion.

Having thus described my invention it will be seen that changes and modifications may be made 45 therein by those skilled in the art without departing from the spirit and scope of the invention and I do not wish to be limited to the details herein disclosed, but what I claim is:

1. In a needle motion for an Axminster loom, a 50 drum to be rotated to actuate the needle, a pinion fixed with respect to the drum, an arcuate set of teeth to mesh with the pinion, a locking surface concentric with the arcuate teeth and moving therewith and extending beyond the teeth 55 in the direction of motion of the latter, and a lock rotating with the pinion and having a curved surface to engage said concentric surface to prevent rotation of the pinion when said concentric surface moves with respect to the lock. 60

2. In a needle motion for an Axminster loom, a needle actuating drum to be rotated, a shaft to which the drum is secured, a pinion secured to the shaft, a constantly rotating actuator member, a rack having gear teeth to mesh with the pinion, 65 connections between the actuator member and rack to reciprocate the latter and give the same a stroke the first part of which is needle actuating and the last part of which is non-actuating with respect to the needle, means moving with the rack presenting a locking surface extending beyond the teeth of the rack, and a lock rotating with the pinion and having a surface to engage the locking surface of the rack, the actuator member causing the 70 75

toothed part of the rack to rotate the pinion during the needle actuating part of the stroke of said rack and causing engagement of the locking surface of the segment and the lock of the pinion to prevent rotation of the pinion during the non-actuating part of the stroke of the rack.

3. In a needle motion for an Axminster loom, a needle actuating drum to be rotated, a shaft to which the drum is secured, a pinion secured to the shaft, a constantly rotating actuator member, a segment gear to mesh with the pinion, a connector between the actuator member and segment to reciprocate the latter as the member rotates and give said segment a stroke the first part of which is working and the last part of which is non-working, means on the segment presenting an arcuate locking surface, and a lock secured to and rotating with the pinion for engagement with the locking surface, the actuator member to cause the segment to rotate the pinion during the working part of the stroke of the segment and thereafter cause engagement of the locking surface of the segment with the locking means of the pinion during the non-working part of the stroke of the segment.

4. In a needle motion for an Axminster loom, a needle actuating drum to be rotated, a shaft to which the drum is secured, a pinion secured to the shaft, a constantly rotating actuator member, a segment gear to mesh with the pinion, a pivot for the latter, a connector between the actuator member and segment gear to reciprocate the latter about the pivot and give the segment a stroke the first part of which is needle actuating and the last part of which is non-actuating with respect to the needle, means on the segment presenting a locking arcuate surface concentric with the pivot, and a lock secured to and moving with the pinion having an arcuate surface to engage the locking surface, said actuator member causing the segment to rotate the gear during the needle actuating part of the stroke and causing cooperation between the locking surface of the segment and the lock of the pinion to prevent rotation of the latter during the non-actuating part of the stroke of the segment.

5. In a needle motion for an Axminster loom, a

needle actuating drum to be rotated, a pinion fixed with respect to and rotating with the drum, a segment gear to mesh with and rotate the pinion, a pivot for the segment, a constantly rotating actuator connected to the segment and giving the latter a stroke the first part of which is a working stroke to rotate the pinion, means moving with the segment presenting a locking surface concentric with said pivot, and a lock fixed with respect to and rotating with the pinion and having an arcuate surface of substantially the same radius as the surface of the said first locking surface, said first locking surface extending beyond the teeth of the segment and brought into locking relationship with respect to the lock moving with the pinion by motion of said segment, the locking surfaces when in engagement effective to prevent rotation of the pinion while the segment moves after the conclusion of the working part of the stroke.

6. In a needle motion for an Axminster loom, a needle actuating drum to be rotated, a shaft to which the drum is secured, a pinion secured to the shaft, a constantly rotating crank arm, a segment gear to mesh with the pinion, a pivot for the segment gear, a connector between the crank arm and the segment to reciprocate the latter, each continuous motion of the segment to have a needle actuating part and a needle non-actuating part derived from the crank arm, means carried by the segment to extend beyond the teeth thereof presenting a locking surface concentric with the pivot, and a lock secured to the pinion and having an arcuate surface of the same radius as that of the locking surface on the segment, the crank arm to cause the teeth of the segment to rotate the pinion during the needle actuating part of the continuous motion of said segment, and the crank arm to move the locking surface of the segment into engagement with the arcuate surface of the lock at the conclusion of the needle actuating stroke to prevent rotation of the pinion throughout the non-actuating part of the continuous motion of the segment.

WILLIAM W. ROBERTSON.
